Attorney

UNITED STATES PATENT OFFICE.

HARRY W. SHULL, OF BROADWATER, NEBRASKA, ASSIGNOR OF ONE-HALF TO JAMES P. MURPHY, OF ALLIANCE, NEBRASKA.

PITMAN BOX FOR USE ON MOWERS AND BINDERS.

Application filed February 16, 1923. Serial No. 619,482.

To all whom it may concern:

Be it known that I, HARRY W. SHULL, a citizen of the United States, residing at Broadwater, in the county of Morrill and 5 State of Nebraska, have invented a new and useful Pitman Box for Use on Mowers and Binders, of which the following is a specification.

My invention relates to improvements in 10 pitman boxes. The objects of my improvements are, first, to eliminate play and vibration, and provide a constantly tight boxing, second to extend the period of usefulness of the bushing, third, to extend the 15 period of usefulness of the wrist pin, fourth, to obtain a more perfect lubrication, and fifth, by reducing the play and vibration of the wrist pin in the boxing, to save the sickle blade and other parts of the mower or binder 20 from wear and breakage thus extending the period of usefulness of the machinery, as well as providing a means of quickly repairing or replacing the worn or broken parts.

I attain these objects by the mechanism illustrated in the accompanying drawing, in which—

Figure 1, is an ordinary type of pitman box made of one solid piece with one piece 30 bushing and side lubrication of the character in present use; Fig. 2, shows the improved pitman box; Fig. 3, is the two sections of the pitman box separated; Fig. 4, shows the bushing in two sections; Fig. 5, is 35 the wedge or shim.

Similar numerals refer to similar parts throughout the several views.

The pitman box is made in two sections, (Figs. 2 and 3,) 1, 2 held together on the 40 front side by two bolts 3 extending through holes 13 and 14, and at the back side by the pitman straps 4 and bolt 15 which clamp onto the boxing at 11. The bushing 5 fits into the lower section of boxing and is held 45 firmly in place by a raised place on the under surface which fits into groove at 6, the upper section of bushing 7 being held in place by a depression 8 in the center on the top side which serves as an opening for lubrication 50 at 9 which is furnished from the hard oil cup 10. The wedge or shim 12 is slipped be-

tween parts 1 and 2 so that said parts will fit accurately upon the wrist pin. As the bushing 5 and 7 becomes worn the width of the shims 12 is reduced so the boxing can 55 be drawn closer together on the wrist pin and vibration minimized. Oil from the hard oil cup 10 enters the boxing 1 at 9 so the lubrication is equally distributed about the wrist pin.

I claim:

1. A pitman box for mowers, binders and the like wherein the pitman is formed of an arm adapted for axial and rocking movement, operated from a rotating crank having a crank pin, comprising separable bearing sections formed with substantially semi-cylindrical crank pin receiving portions, and laterally extending flanges from the ends of the semi-cylindrical portions, 70 semi-cylindrical bushings removably fitted in the corresponding portions of said bearing sections for providing a bearing on the crank pin, means for holding the bushings against movement in the bearing sections, 75 removable shims between the flanges of the sections, and means cooperating with the flanges of each section for securing the sections in bearing forming relation, said shims permitting the adjustment to take up wear, 80 and straps secured to the flanges at one end of each section by the securing means therefor, and to the sides of the pitman for mounting the bearing on the end of the pitman, the bearing sections being adjustable 85 transversely with relation to the axis of said pitman.

2. A pitman box for mowers, binders and the like, wherein the pitman is formed of an arm adapted for axial and rocking movement, and adapted for operation from the 90 rotating frame having a laterally extending crank case comprising separable semi-cylindrical bearing sections having flanges extending in opposite direction from the opposite ends thereof, bushing removably mounted in the bearing portion of each section, means connected with corresponding flanges of each bearing section for securing said sections in bearing forming relation, removable shims positioned between the flanges 95 of said sections for adjusting the relation 100

thereof, a pair of strips mounted on the side of the pitman and projecting beyond the end thereof, said bearing having the flanges at one end of each section projecting between said strips and secured thereby by said securing means, said bearing being adapted to receive the crank pin extending

from said crank arm to provide a bearing for the pitman rod, said bearing section being adjustable laterally to the axis of said pitman, for compensating for wear in the bearing on the crank pin. 10

HARRY W. SHULL.
